United States Patent Office

Des. 232,403
Patented Aug. 20, 1974

232,403

STACK TABLE

Arnold C. Martinelli, Lake Shore Drive,
Rawdon, Quebec, Canada

Filed Jan. 19, 1973, Ser. No. 324,993

Term of patent 14 years

Int. Cl. D6—03

U.S. Cl. D6—146

FIG. 1.

FIG. 2.

FIG. 3.

FIG. 1 is a top plan view of a stack table showing my new design;

FIG. 2 is an elevational view thereof; and

FIG. 3 is a bottom plan view thereof.

I claim:

The ornamental design for a stack table, as shown.
